FEEDER FOR PULVERULENT MATERIAL

Maurice M. Wheldon, Monessen, Pa.

Application June 24, 1938, Serial No. 215,649

1 Claim. (Cl. 221—125)

My invention relates to feeding apparatus for powdered or granular material wherein the material is constantly supplied to a rotating table and from there deflected at desired rates to a conveyor or a receptacle.

One use of the apparatus as shown in the accompanying drawings would be in the supplying of iron ore, blast furnace flue dust, fine coke or the like, to a conveyor belt, for transfer to a sintering oven. The apparatus could be put to various other uses such, for example, as supplying materials to a concrete mixer, one feeding device being employed for depositing the dry cement on a conveyor belt, another feeder for supplying sand, and another for supplying gravel to the belt, in proper relative proportions; pug mills; brick mixtures; fertilizer mixtures, etc.

In apparatus of this character as heretofore employed, there is difficulty in maintaining proper feed of material, in accurately measured quantities, and they have the further objection that there is too great abrasive action of the material, on various parts of the feeding apparatus.

My invention has for one of its objects, the provision of means whereby the feeding apparatus may be adjusted to feed material at a rate which may be determined with precision.

Another object of my invention is to provide feeding apparatus for materials of the character referred to, wherein there is a minimum of abrasive wear as between the material and the feeding apparatus.

One form which my invention may take is shown in the accompanying drawings wherein Figure 1 is a plan view of the apparatus, partly in section; Fig. 2 is a partial side view thereof; Fig. 3 is a view taken on the line III—III of Fig. 1; Fig. 4 is a view taken on the line IV—IV of Fig. 2, and Fig. 5 is a view taken on the line V—V of Fig. 4.

As shown more clearly in Fig. 3, the apparatus is shown as mounted upon a foundation 6, to which is secured a base plate 7, that has a pair of annular flanges 8 which extend into annular recesses in the underside of a rotating table 9, to thereby prevent horizontal displacement of the table relative to the base plate. Anti-friction bearings 10 are interposed between the table and the base plate. The base plate 7 carries a pair of bearings 11 through which a drive shaft 12 extends, the shaft being driven from any suitable source of power. A pinion 13 is carried by the shaft 12 and has driving engagement with a ring gear 13a that is secured to the underside of the table 9.

Material is supplied to the table 9 from a bin or hopper 14 that may be suspended from suitable framework, not shown. The hopper 14 discharges through a cylindrical discharge spout 15, which is suspended from the hopper. The member 15 contains an inner flange 16 upon which is supported a flow plate 17 having a circular opening 18 at its central portion. This plate can readily be replaced.

The material will flow from the hopper 10 through the opening 18 and accumulate upon the table 9 in a pile of truncated conical form, somewhat as indicated by the numeral 19, the diameter of the pile being substantially constant regardless of the quantity of material in the hopper 14. The table 9 will usually be rotated at a constant speed and at a rate which will not create such centrifugal force as will cause "throw" of material toward the periphery of the table. The cylindrical spout 15 has an opening 20 through its wall, of an area not less than the area of the opening 18 in the plate 17, and one edge of the opening is provided with a renewable wearing plate 21 that can be replaced when it becomes worn through abrasive action of the material. Of course, the material does not touch the plate 21 unless it is being fed at the maximum rate.

A bracket 22 is secured to the wall of the spout 15 by screws 23, and carries vertically-spaced webs or flanges 24 that have thrust engagement with the adjacent edge of the member 15. A plate 25 is secured to the member 15 by a bracket 26. A wear plate 27 is secured to the face of the bracket 22 and the plate 25. The bracket 22 carries a knuckle member 28 through which extends a hinge pin 29. A plow or scraper 31 has at one end a knuckle through which the pin 29 extends and carries a handle 32 by means of which the scraper may be swung about this pivot. A flange 33 is provided on the upper edge of the cut-out portion 20 of the member 15, and carries an arcuate key plate 34 that overlies the handle 32 and is provided with holes for the reception of a pair of keys 35 that are disposed at opposite sides of the handle 32 to hold it set in positions of adjustment on its pivot.

It will be seen that with the blade 31 positioned close to the wall of the spout 15, the inner end of the blade will not be engaged by the material, and hence there will be no discharge of the material even during rotation of the table 9. In order to feed material, the blade is rocked about its pivot so that its inner end will dip into or bisect the pile of material at 19 a desired distance and, be-

cause of the rotation of the table 9, a portion of the pile of material will be deflected along the blade 31 and the deflector plate 27 to the periphery of the table, whence it will fall upon a conveyor 36. The volume of material thus deflected from the pile will, of course, depend upon the extent to which the blade is moved into the pile. The size of the opening 20 is such that even though the inner edge of the blade be moved 10 clear to the center of the pile, and hence maximum discharge of material thereby obtained, there will be no crowding of the material at said opening—with consequent wear. Likewise, the diameter of the spout 15 is such that there will be 15 no crowding of material against the peripheral wall thereof. Such crowding of the material would not only result in inaccurate rate of feed, but cause rapid wear on the table, wall and bottom of 15. Since at normal rates of table speed, 20 the pile of material at 19 will be of constant volume, a very accurate rate of feed can be obtained through simply adjusting the depth to which the blade 31 is set into the pile.

The scraper 31 is preferably positioned in approximately tangential relation to the pile instead of radially thereof, so as to reduce to a minimum the pressure and friction of the mate-

rial against the blade and to also facilitate movement thereof to the edge of the table 9.

It will be understood that a plurality of these feeding devices can be employed to supply the conveyor 36 with definite proportions of various materials which are to be intermingled.

I claim as my invention:

Feeding apparatus comprising a hopper having a cylindrical discharge mouth provided with an opening through its side wall at its lower edge, 10 a table disposed adjacent to the lower edge of said mouth, a horizontally-positioned flow plate in said mouth above said opening, said plate having a central orifice for flow of material therethrough, from the hopper, the orifice being of such reduced diameter relative to the diameter of the mouth as to form a pile of material centrally on the table that is out of contact with the lower peripheral wall of the said mouth, means for rotating the table and the pile of material thereon, and a 15 scraper plate extending through said opening and positioned in tangential relation to said pile, for deflecting material from said pile and through said opening to the edge of the table, the plate being removably supported in said mouth and 20 having its central opening unobstructed.

MAURICE M. WHELDON.
